UNITED STATES PATENT OFFICE.

WILLIAM H. BAKER, OF MONTREAL, QUEBEC, CANADA.

SPRINKLER.

Application filed April 13, 1917, Serial No. 161,823. Renewed March 31, 1923.

To all whom it may concern:

Be it known that I, WILLIAM H. BAKER, a citizen of the United States of America, and resident of the city of Montreal, in the Province of Quebec and Dominion of Canada, have invented certain new and useful Improvements in Sprinklers, of which the following is a full, clear, and exact description.

10 This invention relates to improvements in sprinklers, and the object is to provide a simple and efficient sprinkler, comprising a minimum number of parts.

15 A further object is to provide a sprinkler, which will be quick in action and will overcome the difficulty of valves sticking part way open.

20 The device consists briefly of a body, yoke and valve of any suitable construction, and a valve holding strut preferably of the duck-bill type. The strut comprises a pair of members and a holding lever therefor having its long arm buried in one of the strut members.

25 In the drawings which illustrate the invention:—

Fig. 1 is a side elevation of the sprinkler head, part of the yoke being broken away.

30 Fig. 2 is a vertical longitudinal section of the strut.

Fig. 3 is a cross sectional view of the strut on the line 3—3, Figure 1.

Fig. 4 is a plan view of the strut, the solder being removed.

35 Referring more particularly to the drawings, 11 designates the body of a sprinkler having a yoke 12, a deflector 13 attached by means of a screw 14, which also serves to bind the strut in place. The body is provided with a valve 15. The end of the screw 14 and the valve 15 are provided with conical or otherwise suitably shaped depressions 16 arranged axially in line, and designed to receive the points 17 of the strut

40 members 18 and 19. As shown in the drawings, the strut is of the duck-bill type, the members bearing pivotally on one another at a point 20 slightly out of the axial or pressure line of the head, so that pressure applied to the points 17 tends to separate the extremities of the members. The free end of the member 18 projects beyond the end of the member 19, and in the projecting portion is provided an elongated aperture

45 21. The member 19 is provided with a deep groove 22 extending from the free end to

adjacent the point 17, and from the outer edge nearly through the member. This groove at its bottom is substantially parallel with the abutting edges of the members, so that owing to the roughly triangular formation of the member 19, the groove deepens from the free end toward the fixed end of the member. A holding lever 23 is provided having the long arm 24 thereof lying in the groove 22, and having the short arm 25 thereof offset or hooked so as to pass through the aperture 21 of the member 18 and engage the remote surface of the member. The aperture 21 is then filled with solder or other fusible material 26, so as to prevent corrosion of the parts. The groove 22 is also filled with solder or fusible material 27 which holds the long arm of the lever securely in place and effects a secure 75 connection between the strut members. It will be readily noted in Figure 2 that the greatest mass of fusible material is located at the extreme end of the lever, and that this fusible material is enclosed in the greatest mass of metal of the strut. The obvious result is that the metal at the extreme end of the lever arm is the last to soften, and therefore the lever is entirely free when its end is released.

50 The operation and advantages of the device are apparent. Pressure on the points of the strut members tends to separate the ends thereof. The holding lever 23 is fulcrumed at the extremity of the member 19, and with its short arm 25 engages the extremity of the member 18. Thus, the separating action of the members tends to swing the long arm 24 of the lever out of the slot 22. This movement is resisted by the fusible material 27. On a rise of temperature, the extremity of the strut which projects beyond the head and yoke is naturally the first to heat, as it is most exposed and as the mass of metal is small in comparison with the inner end of the strut. Therefore, the fusible material 26 melts and flows out, and also material 27 at the outer end of the slot, leaving only the fusible material at the inner end of the slot holding the extremity of the long arm 24. When the temperature of the strut rises sufficiently, the remainder of the material 27 softens, and as practically the whole length of the lever is now free of obstruction, so that the full pressure is exerted on the end, it is obvious that this end will

readily tear itself out of the softened fusible material. The contact surface of the member 19 is sufficiently large, so that the solder gets a firm grip and a sufficient bulk of solder is present to prevent any creeping of the parts. While the strut has been illustrated as of the duck-bill type, it will be readily understood that the feature of burying the lever may be applied to other forms 5 of strut, and also the feature of locating the greatest mass of solder at the end of the lever and at a point where it is so protected as to be the last to fuse. It will also be understood that the invention is not 10 limited to the specific details shown, and that various changes may be made therein, such as the transference of the aperture from the member 18 to the lever 23, so that the strut member passes through the lever in 15 20 place of the lever through the strut member. Obviously such a change does not in any way affect the main feature of the invention, which is the quick and absolutely certain action of the device once a certain temperature has been reached, and the removal of all material which would tend to delay the 25 quick separation of the parts.

So far no mention has been made of the method of forming the parts, and it will 30 be understood that these may be either cast, machined, stamped or pressed, or built up of separate pieces, especially in the case of the member 19.

Having thus described my invention, what 35 I claim is:—

1. In a sprinkler, a body, a yoke, a valve, and a strut in compression between the yoke and valve holding the latter, said strut comprising a pair of members one having 40 a groove of varying depth, a bearing surface on the other member and a holding lever engaging at one end with said bearing surface and engaging at the opposite end in said groove, and lever holding material of 45 low fusibility filling the groove above the lever.

2. In a sprinkler, a body, a yoke, a valve, and a strut in compression between the yoke and valve holding the latter, said strut 50 comprising a pair of members of unequal length tapering toward their free extremities, the shorter of said members having a groove in the edge thereof remote from the other member, said groove varying in 55 depth from the free end of the member, a holding lever fulcrumed at the end of said shorter member, and having the longer arm thereof occupying the member groove and the shorter arm thereof operatively engaging the projecting end of the longer member, and fusible material in said groove holding 60 the lever.

3. In a sprinkler, a strut comprising a 65 pair of members, one having a groove of varying depth, a holding lever for said strut

members fulcrumed at the extremity of said groove member and having the extremity of its long arm located in the deepest point of the groove, the shorter arm of said lever operatively engaging the other strut member, and readily fusible material filling the groove whereby the greatest mass of fusible material occurs at the extremity of the lever.

4. In a sprinkler, a strut comprising a 75 pair of members, one of them having a recess, and a reversely curved holding lever operatively engaging said members and having one of its ends located at the bottom of said recess, and a filling of fusible material 80 in the recess above the extremity of the lever confining the same in the recess.

5. In a sprinkler, a strut comprising a 85 pair of members, a lever connecting said members, one of said members having a recess for the reception of the lever, and a filling of fusible material in said recess holding the lever, the recess being shaped to hold a greater depth of fusible material at the extremity of the lever than at any other 90 point.

6. In a sprinkler, a strut comprising a 95 pair of members in pivotal engagement adjacent one end, a connecting lever for the members, a body of readily fusible material holding said lever, and a recess in one of the members for the reception of said lever and fusible material, said recess being formed to contain the greatest mass of fusible material in proximity to the greatest 100 mass of metal in the strut and at the extremity of the lever, whereby the material at the extremity of the lever will be the last to fuse.

7. In a sprinkler, a strut comprising a 105 pair of members of unequal length in pivotal engagement adjacent one end of the strut, the shorter of said members being grooved on the side remote from the other member, and the longer member being apertured in its projecting extremity, and a holding lever having one arm thereof passing through the aperture of the longer member and operatively engaging the member and the longer arm thereof seated in the groove of the other member, and a filling 110 of fusible material in said groove holding the lever.

8. In a sprinkler, a strut comprising a 120 pair of substantially triangular members arranged for pivotal movement at adjacent corners, one of said members being recessed on the edge remote from the other member, a holding lever for said members having one of its arms operatively engaging with the unrecessed member and the other arm engaging in the recess of said recessed member, and fusible material holding the lever in the recess.

9. In a sprinkler, a collapsible strut com- 130

prising a pair of members, one of them recessed and the other apertured, a lever holding the strut against collapse and located at one end in the recess of the recessed member, and at the other end passing through and hooking onto the apertured member, and fusible material in the recess holding the lever, said fusible material engaging the lever through a large part of its

length and being so distributed relatively 10 to the recessed member that the material at the extremity of the lever will be the last to fuse, whereby the lever will be held until clear of fusible material elsewhere throughout its length.

15 In witness whereof, I have hereunto set my hand.

WILLIAM H. BAKER.
